(57) **CLAIM**

The ornamental design for a tripod, as shown and described.

DESCRIPTION

FIG. 1 is a front and top perspective view of a tripod, showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the tripod, showing the tripod in an extended position;

FIG. 10 is an enlarged view of a portion indicated with numeric 10 in FIG. 1;

FIG. 11 is an enlarged view of a portion indicated with numeric 11 in FIG. 1;

FIG. 12 is an enlarged view of a portion indicated with numeric 12 in FIGS. 2; and,

FIG. 13 is an enlarged view of a portion indicated with numeric 13 in FIG. 2.

The dashed broken lines in the figures illustrate portions of the tripod that form no part of the claimed design. The dash dot dash lines in FIGS. 1, 2, 10, 11, 12 and 13 are for the purpose of disclosing enlarged detailed views.

1 Claim, 13 Drawing Sheets
